United States Patent Office

Des. 206,307
Patented Nov. 22, 1966

206,307

TOASTER

Robert O. Ernest, Oak Park, Ill., assignor to Sunbeam
Corporation, Chicago, Ill., a corporation of Illinois

Filed Oct. 21, 1965, Ser. No. 87,709

Term of patent 14 years

(Cl. D81—10)

Fig. 1.

Fig. 2.

Fig. 6.

FIG. 1 is a perspective view of a toaster showing my new design;

FIG. 2 is a top plan view thereof;

FIG. 3 is a side elevational view thereof;

FIG. 4 is a rear elevational view thereof;

FIG. 5 is a sectioned elevational view taken along line 5-5 of FIG. 3; and

FIG. 6 is an enlarged fragmentary sectioned view taken along line 6-6 of FIG. 1.

The dominant features of my design reside in the portions shown in full lines.

I claim:

The ornamental design for a toaster, as shown and described.
